UNITED STATES PATENT OFFICE.

JOHN T. GARY, OF ATLANTA, GEORGIA.

TROLLEY-HANGER.

1,114,130.

Specification of Letters Patent. Patented Oct. 20, 1914.

Application filed October 11, 1913. Serial No. 794,664.

To all whom it may concern:

Be it known that I, JOHN T. GARY, a citizen of the United States, residing at Atlanta, in the county of Fulton and State of Georgia, have invented certain new and useful Improvements in Trolley-Hangers, of which the following is a specification, reference being had to the accompanying drawings.

10 This invention relates to new and useful improvements in trolley hangers and the primary object of the invention is to provide a device of this character which may be quickly and readily applied to use and 15 adjusted, as desired.

A further object of the invention resides in providing a device which is capable of application to use in connection with wires of various sizes and a still further object 20 of the invention resides in providing a device which is simple and durable in construction, inexpensive to manufacture and one which will be very efficient and useful in operation.

25 With these and other objects in view, the invention consists in the novel features of construction, combination and arrangement of parts as will be hereinafter referred to and more particularly pointed out in the 30 specification and claims.

In the accompanying drawing forming a part of this application, Figure 1 is an elevation of the device applied to use. Fig. 2 is a top plan view of the body portion 35 thereof. Fig. 3 is a bottom plan view of the cap member, and Fig. 4 is a section through the body and cap member applied together.

In describing my invention, I shall refer to the drawing in which similar reference 40 characters designate corresponding parts throughout the several views and in which—

1 indicates the body of my improved hanger having formed at diametrically opposite points thereon the projecting arms 2 and formed on said arms are flanges which are bent to form arcuate ears 3, the same being adapted to receive therein a suspension or span wire 4. The upper face of the body 1 which is raised to a plane slightly above 45 the plane of the arms 2, is grooved arcuately, as shown at 5 to receive therein said suspension wire when the hanger is applied to use, and said body 1 is provided with a central bore 6. A cap member 7 is adapted to 50 be applied to the top face of said body 1,

the same being provided with a central opening 8 to align with the bore 6 of the body. The contacting face of said cap 7 is provided with a plurality of arcuate intersecting grooves 9 which are adapted to coöperate with the groove 5 of the body 1. The grooves 9 are of various depths, so as to accommodate wires of various sizes, it being understood that in the application of the cap member to the body, one of said grooves 65 9 aligns or registers with the groove 5 in said body. In order to secure the cap member to the body, a bolt 10 is introduced through the alining bores 6 and 8 of said members, so that the threaded end of said 70 bolt will project below the under face of the body 1. A split spring washer 11 is applied to the bolt between the head thereof and the upper face of the cap member 7 and a member 12 which, for convenience, 75 may be termed a thimble, is engaged with the lower threaded end of said bolt and adapted to be turned home thereon to tightly clamp against the under face of said body 1. When so clamped against said body, 80 the cap member and body will be securely held together and the flanges on the arms 2 are then adapted to be disposed into engagement with the span wire 4, while the lower end of the thimble 12 is suitably engaged with the trolley wire 13. When the 85 members are so secured together, the same are not adapted for casual disengagement, but may be quickly and readily engaged, when desired and if through constant use, 90 the threads of the bolt 10 become worn so as to cause a play between said members, said play will be taken up by the action of the washer 11, which is applied on the bolt between the head thereof and the upper face 95 of the cap member.

From the foregoing description of the construction of my improved device, the manner of applying the same to use will be readily understood and it will be seen that 100 I have provided a device which is simple and durable in construction, inexpensive to manufacture and one which will be very efficient and useful in operation.

Among the advantages possessed by my 105 device, it will be particularly noted that owing to the peculiar construction of the hanger, it is impossible for it to burn out on account of loose or poor connections. This is a serious objection to most feed hang- 110

ers in use and as my improved hanger avoids this objection, its advantages will at once be apparent.

While I have particularly described the 5 elements best adapted to perform the functions set forth, it is obvious that various changes in form, proportion and in the minor details of construction may be resorted to without departing from the spirit 10 or sacrificing any of the principles of the invention.

Having thus described this invention, what I claim is:—

1. In a trolley hanger, a body member 15 having a pair of oppositely extending arms formed thereon, the upper face of said body having a transversely extending arcuate groove formed therein to receive a suspension wire, the upper face of said body being 20 disposed in a plane slightly above the upper faces of said arms whereby the base of the groove in the body is disposed in the same plane as the upper faces of said arms to provide an even bearing surface for said 25 suspension wire the entire length of the hanger, flanges formed on the outer ends of said arms for engagement with the suspension wire, said flanges being disposed to one

side of the longitudinal center of said groove to force said suspension wire to frictionally 30 engage one side wall of said groove, a cap member for application to said body to retain the wire in place therein, and means to secure said cap member and body together. 35

2. In a trolley hanger, a body member 40 having a pair of oppositely extending arms formed thereon, the upper face of said body having a transversely extending groove formed therein to receive a suspension wire, flanges formed on the outer ends of said 45 arms for engagement with the suspension wire, a cap member adapted for application to the upper face of said body, said cap member having a plurality of transversely extending grooves of various depths formed 50 in the contacting face thereof, any one of said grooves being adapted for co-operation with the groove in the upper face of the body, and means to clamp said cap member and body together.

In testimony whereof I hereunto affix my signature in the presence of two witnesses.

JOHN T. GARY.
